UNITED STATES PATENT OFFICE

WILLIAM GORSON LITTLE, OF SHOREHAM, ENGLAND.

CARBURETER.

1,214,252.

Specification of Letters Patent. Patented Jan. 30, 1917.

Application filed August 21, 1916. Serial No. 116,155.

To all whom it may concern:

Be it known that I, WILLIAM GORSON LITTLE, a subject of the King of Great Britain, residing in Shoreham, England, have invented a certain new and useful Improvement in Carbureters, of which the following is a specification.

This invention relates to improvements in carbureters for internal combustion engines and, more particularly, to a carbureter of that type wherein hinged flaps controlled by a spring or springs and a dash pot are employed as regulating elements of a variable choke tube in which the fuel nozzle is arranged; wherein the air necessary to complete the combustible mixture is drawn through a suitable inlet and passes through said choke tube in operative relation to said nozzle; and wherein the flaps open more or less in accordance with the prevailing suction influence and in their action control the air admission, the quantity of air admitted being greater or less accordingly as the flaps are more or less widely open or spaced.

The principal objects of the present invention are to provide a simply constructed carbureter of the broad or general type referred to whose parts are easily accessible for cleaning or renewal; in which special provision is made for the easy starting of the engine when the flaps are in their closed position and further provision is made for the temporary positive control of the relation of the flaps in order to increase the richness of the mixture, as in starting and hill climbing; and wherein the dash pot is so arranged and operatively connected to the flaps as to insure of their smooth or regular action, thereby eliminating fluttering and providing for a steady supply of the fuel mixture throughout the range of engine speeds.

With the above objects in view the invention consists in certain novel features of structure and combination which will appear as the description proceeds.

In the accompanying drawing, Figures 1 and 2 are longitudinal sections in planes at right angles through an example of a carbureter according to the invention. Fig. 3 is a view partly in section on the line 3-3 of Fig. 2.

The flaps 1, 1' having flanges 26° (Fig. 3) constitute the parts of the split choke tube. They are hinged at the pins 2, 2' located in a casing 3 of the carbureter tube and automatically turning on these pins so as to

allow the flow of a larger volume of air, as the throttle valve 4 is opened more widely and a greater suction is produced by the speed of the engine.

5 is a petrol jet; in the example shown the jet comprises five small openings 6 in communication with a passage 7 leading through a piece 8 to a duct in connection with the float chamber. The jet can be readily withdrawn from the tube by unscrewing it from the connection to the float chamber. The tube is carried on the jet, being held in position by the washer 9 and nut 10. Between the casing 11 and the tube 3 is a space containing air warmed from the exhaust pipe of the engine and the tube 3 has air inlet openings 8' by which it communicates with said space.

The outward movement of the hinged parts 1, 1' is opposed by a spring 12, one end of which is attached to a pin 14. Arms 13, 13' secured to the hinged flaps 1, 1' are pivoted by pins 16, 16' to links 17, 17'; a pin 18 passes through the lower ends of these links and through a forked head 19 of a rod 20 which is pulled down by the spring 12. This downward movement closes the hinged flaps 1, 1'. The rod 20 is secured to a piston 21 moving in an oil cylinder 22 and acting as a device to damp the oscillations of the parts 1, 1'. The tension on the spring 12 can be adjusted by a clamping device 23.

A lever 24 pivoted at 25 and engaging with the pin 14 can be held up on starting the engine, so as to keep the flaps 1, 1' closed against the inrush of air and in a position to reduce the supply of air at the moment of starting the engine.

In the closed position, the flanges 26° (Fig. 3) abut against the sides of the petrol jet 5, so that there is still some space left for the passage of air on either side of the jet; the flanges, which stiffen or strengthen the flaps, have a close sliding fit against the adjacent walls of the tube 3 and thereby serve to prevent any leakage of air between the flaps and the sides of the tube.

A ring 28 is mounted to be turned by means of a button 27 on the casing 11. In this ring are air inlet openings 28 corresponding with those marked 29 in the casing 11. The ring can be turned through an angle equal to the diameter of a perforation, so that the two sets of perforations may be brought into registration, or any degree of registration, with each other.

Having thus described the nature of the said invention and the best means I know of carrying the same into practical effect, I claim:—

- 3 1. A carbureter comprising a casing, a petrol nozzle within the casing, hinged flaps arranged at opposite sides of the petrol nozzle, a dash pot situated below said casing and co-axial therewith, and a pair of 10 links connected to the respective flaps and to the movable member of the dash pot whereby the flaps in their movements toward or from one another operate said movable member.
- 15 2. A carbureter comprising a casing, a petrol jet within the casing, hinged flaps within the casing, flanged edges to the said

flaps, adapted normally to abut against the said petrol jet, a dash-pot situated below the said casing, links connecting the movable member of the said dash-pot with the said flaps, an adjustable spring connected with the said movable member, a lever connected with the said movable member and adapted when pressed to hold the said flaps against the said petrol jet and means for varying the air admission to the said casing. 20 25

In testimony whereof I have signed my name to this specification in the presence of two subscribing witnesses,

WILLIAM GODSON LITTLE.
